UNITED STATES PATENT OFFICE.

OLIVER A. MENTZER, OF LANCASTER, PENNSYLVANIA, ASSIGNOR OF ONE-HALF TO
HENRY E. RANSING, OF LANCASTER, PENNSYLVANIA.

WRENCH.

1,108,602.

Specification of Letters Patent. Patented Aug. 25, 1914.

Application filed May 18, 1914. Serial No. 839,193.

To all whom it may concern:

Be it known that I, OLIVER A. MENTZER, a citizen of the United States, residing at Lancaster, in the county of Lancaster and State of Pennsylvania, have invented certain new and useful Improvements in Wrenches, of which the following is a specification, reference being had therein to the accompanying drawing.

This invention relates to a wrench which may be used for the various uses for which a wrench is employed, but it is especially designed for use with my improved lock bolt and nut, which is described and claimed in my application for United States patent filed December 10, 1913, Serial No. 805,670. Referring to said application, it will be noted that in a general way the invention comprises a bolt having one or more sides flattened, or having a keyway, and upon which a washer is placed, so that it is non-revolvble on the bolt; one surface of said washer being corrugated; while upon this washer is placed a locking washer provided with spring pawls which engage the corrugations on the first washer, and hold the same against rotation in a backward direction as the locking washer is secured to the nut. To release the locking washer it is necessary to raise the spring pawls from engagement with the corrugations on the washer, and at the same time back off the nut from the bolt; and to accomplish this in a sure and quick manner, I have devised the wrench which is the subject of this invention, and which I will now proceed to describe in detail.

With these and other objects in view, my invention consists in certain construction and combination of parts as will hereinafter be fully described and claimed in the annexed specification, and illustrated in the accompanying drawings, which form a part of this application, and in which like figures of reference refer to corresponding parts in all of the views; but it is fully understood that while I have here described my device as herewith shown, that I do not confine myself to the exact design as shown, as slight changes may be made in the construction and combination of the several parts without departing from the spirit of the invention.

Referring to the drawings:—Figure 1, is a side elevation of my wrench as applied to the nut and bolt lock. Fig. 2, is a top plan view of the same. Fig. 3, is a side elevation of a modified form of wrench. Fig. 4, is a top plan view of the same. Fig. 5, is a side elevation of a similar device, which may be employed when the nut is in close quarters and not sufficient room allowed for the use of the wrench.

In the drawings, the nut is designated by the numeral 1; the corrugated washer by 2; the locking washer by 3; the spring pawl by 4, and the corrugations by 19, and the bolt by 5.

As shown by Fig. 1, the wrench comprises a body portion or handle 6, which is provided at one end with a nut engaging portion grooved out as at 7, to engage the nut 1, and rest upon the upper surfaces thereof. Depending from the lower surfaces of said end and integral therewith are two curved arms 8, which have their ends tapered as at 9, to engage the tits on the spring pawls 4, in such a manner that when pressure is exerted on the wrench, the portion 7, acts as a lever, and the arms 8, raise the pawls 4, out of engagement with the corrugations 19; while at the same time the nut may be turned by the wrench.

The modification shown in Figs. 3, and 2, only differs from the above construction in that the pawl lifting arms 13, are part of the bifurcated ends of a finger lever 12, which is pivoted at 14, upon the lever 10, and by pressing the levers 10, and 12, together, the pawls are released.

The modification shown in Fig. 5, comprises a yoke 17, having depending arms 15, and pawl engaging hooks 16, while a wedge 18, is driven between the yoke 17, and the head of the bolt 5, thus raising the pawls.

Having thus described my invention what I claim as new, and desire to secure by Letters Patent is:—

1. A wrench of the class described having a bifurcated end adapted to engage the top and sides of the nut, and curved arms depending therefrom and adapted to engage the nut locking means and release the same.

2. In combination with a nut locking device comprising two washers, one being cor-

rugged and the other provided with pawls
engaging the same, of a wrench having an
end portion adapted to engage the face and
sides of the nut and a depending portion
5 adapted to engage the pawls and raise the
same out of engagement when pressure is
exerted on said wrench.

In testimony whereof I affix my signature
in presence of two witnesses.

OLIVER A. MENTZER.
